VENTURI DUST COLLECTOR

William Spencer Bowen, Westfield, N. J.

Application April 19, 1941, Serial No. 389,261

11 Claims. (Cl. 183—80)

The present invention relates to separating and collecting mechanism by means of which entrained particles may be separated from an entraining fluid, and embodies, more particularly, an improved form of separating and collecting mechanism by means of which the particles may be separated from the entraining fluid without the building up of pressures within the collecting mechanism.

Devices have heretofore been provided by means of which a fluid having particles entrained therein is subjected to a whirl in order to cause the particles to be subjected to centrifugal force, and the particles, together with as small an amount as possible of the entraining fluid, are separated by skimming from the main flow of fluid. This is illustrated in applicant's prior Patent No. 2,082,242.

It has been found, in operation of devices of this character, that there is a tendency to build up a back pressure within the collecting mechanism and thus to reduce the efficiency of collection.

In accordance with the present invention, it is proposed to provide a mechanism by means of which the tendency to build up back pressures in the collecting mechanism may be avoided, thus materially improving the efficiency of collection.

A further object of the invention is to provide a mechanism by means of which the fluid that is skimmed off with the particles is returned to the main body of fluid flowing through the device at a point beyond the skimming element in the direction of flow of the fluid through the device.

A further object of the invention is to provide a device of the above character wherein the skimmed fluid and particles are maintained in a relatively quiescent stage and treated in such fashion that the particles are collected while the excess fluid is returned to the main separating device.

A further object of the invention is to provide a mechanism of the above character wherein the flow of fluid through the device is treated in such fashion that the return of the skimmed fluid to the main flow of fluid through the device is facilitated after the entrained particles have been removed therefrom.

The invention is attained by providing a suitable communication between the collecting chamber and the main chamber of the separating device, such communication permitting the return of fluid to the main chamber beyond the point of separating, in the direction of flow of the fluid therethrough. To this end, the mechanism is

formed with a device for removing the whirl from the main body of fluid after the separation has been accomplished and the skimmed fluid is returned to the main body of fluid from which the whirl has been removed.

Further objects of the invention will appear as it is described in greater detail in connection with the accompanying drawings, wherein:

Fig. 1 is a view in vertical section, taken through a device constructed in accordance with the present invention.

Fig. 2 is a partial view in section, taken on the line 2—2 of Fig. 1 and looking in the direction of the arrows.

Fig. 3 is a view in end elevation, looking from the left in Fig. 1.

Fig. 4 is a view in end elevation looking from the right in Fig. 1, the mechanism being partly broken away and in section in order to illustrate certain features of the connecting chamber.

Referring to the above drawings, the separating and collecting device is shown as being formed as a venturi having an inlet converging cone 10, a throat section 11, and an outlet diverging cone 12.

The inlet cone is provided with a housing 13 within which spirally arranged vanes 14 are provided in order to subject the fluid bearing entrained particles to a violent whirl or twist, thus subjecting the particles to centrifugal force. The center of the housing 13 may be formed with a stream-lined hub 15 in accordance with the usual practice. It will thus be seen that the fluid bearing the particles in suspension will enter the converging inlet portion 10 with a violent whirling motion, thus throwing the particles outwardly against the converging walls 10.

Adjacent the throat of the mechanism, a secondary converging Venturi cone 16 is provided, being spaced from the cone 10 to provide an annular slot 17 through which the particles pass as they are skimmed from the main stream of fluid flowing through the device. The secondary cone 16 is provided with a plurality of vanes 18 to remove the twist or whirl from the fluid flowing through the device in order that it may flow through the throat 11 of the venturi with a smooth lamellar streamline flow. In this fashion, and in accordance with the recognized laws governing the operation of a Venturi section, the velocity in the throat section 11 is greatly increased and the pressure in such section decreased. The fluid then flows out through the expanding cone 12 and is carried away in any desired fashion.

About the throat section of the mechanism

is 55

there is provided a collecting chamber 19 having a hopper 20 or other suitable mechanism for collecting the entrained particles that are skimmed off from the main flow through the slot 17. Slots 21 are formed in the throat section 11 of the venturi and communicate with the hopper 20 through suitably arranged baffles 22 to avoid any tendency to continued entrainment of particles in the relatively quiescent fluid in the collecting chamber 19. A partition 23 may be provided to complete a discharge manifold 24 that communicates with the throat section of the venturi 11 through the openings 21 and a cylindrical sleeve 25 is slidably mounted about the throat section 11 and provided with an elongated slot 26 in order that the total area of the openings 21 may be varied as desired. This is accomplished by rotating the sleeve 25 about the axis of the mechanism, as will be readily apparent.

From the foregoing description, it will be apparent that the operation of the device is such that the fluid having particles in suspension is subjected to a violent whirl by means of the vanes 14 upon entering the mechanism. The converging cone 10 increases the velocity of flow of the fluid and, due to the action of centrifugal force, the particles will be directed against the converging walls of the inlet 10 and be skimmed off through the slot 17. At the same time, some of the fluid will be skimmed from the flow of the main fluid and will enter the relatively quiescent collecting chamber 19. The main body of the fluid will enter the secondary entrance cone 16 of the venturi and by means of the vanes 18 will have the whirl removed therefrom. This will cause the fluid to continue through the throat section of the venturi, in which section its velocity is greatly increased, while its pressure is correspondingly reduced. This provides a section of relatively low pressure in the throat portion of the mechanism and the fluid within the chamber 19 is thus drawn off and returned to the main body of fluid that is flowing into the diverging or outlet section 12 of the mechanism.

The baffles 22 facilitate the collection of the entrained particles within the hopper 20 and the openings 21 may be varied in size to adjust the mechanism to the proper operating condition.

While the invention has been described with reference to the specific mechanism shown in the accompanying drawings, it is not to be limited save as defined in the appended claims.

I claim:

1. Separating and collecting mechanism comprising a first chamber through which a stream of particle laden fluid is adapted to flow, means to separate from said stream a portion of said fluid and particles entrained therein, a receiving chamber to receive the said separated fluid and particles, means to establish a substantially smooth lamellar flow in the first chamber beyond the separating means in the direction of flow, and means to return fluid in the receiving chamber back into the lamellar flow in the first chamber.

2. Separating and collecting mechanism comprising a first chamber through which a stream of particle laden fluid is adapted to flow, means to separate from said stream a portion of said fluid and particles entrained therein, a receiving chamber to receive the said separated fluid and particles, means to establish a substantially

smooth lamellar flow in the first chamber beyond the separating means in the direction of flow, and an opening in the first chamber communicating with the region of lamellar flow to return fluid in the receiving chamber to the first chamber.

3. Separating and collecting mechanism comprising a first chamber through which a stream of particle laden fluid is adapted to flow, means to separate from said stream a portion of said fluid and particles entrained therein, a receiving chamber to receive the said separated fluid and particles, means to establish a substantially smooth lamellar flow in the first chamber beyond the separating means in the direction of flow, an opening in the first chamber communicating with the region of lamellar flow to return fluid in the receiving chamber to the first chamber, and means to vary the size of said opening.

4. Separating and collecting mechanism comprising a first chamber through which a stream of particle laden fluid is adapted to flow, means to separate from said stream a portion of said fluid and particles entrained therein, a receiving chamber to receive the said separated fluid and particles, means to establish a substantially smooth lamellar flow in the first chamber beyond the separating means in the direction of flow, an opening in the first chamber communicating with the region of lamellar flow to return fluid in the receiving chamber to the first chamber, and means to prevent entrainment of particles in the returning fluid.

5. Separating and collecting mechanism comprising a chamber through which a stream of particle laden fluid is adapted to flow, means to impart a whirl to the fluid and particles, means to separate from said stream a portion of said fluid and particles entrained therein, a receiving chamber to receive the said separated fluid and particles, means beyond the separating means in the direction of flow to remove the whirl from the fluid, and means to return fluid from the receiving back to the first chamber in the region beyond the whirl removing means.

6. Separating and collecting mechanism comprising a chamber through which a stream of particle laden fluid is adapted to flow, means to impart a whirl to the fluid and particles, means to separate from said stream a portion of said fluid and particles entrained therein, a receiving chamber to receive the said separated fluid and particles, means beyond the separating means in the direction of flow to remove the whirl from the fluid, and an opening in the first chamber beyond the whirl removing means in the direction of flow and communicating with the receiving chamber to return fluid from the receiving to the first chamber.

7. Separating and collecting mechanism comprising a chamber through which a stream of particle laden fluid is adapted to flow, means to impart a whirl to the fluid and particles, means to separate from said stream a portion of said fluid and particles entrained therein, a receiving chamber to receive the said separated fluid and particles, means beyond the separating means in the direction of flow to remove the whirl from the fluid, an opening in the first chamber beyond the whirl removing means in the direction of flow and communicating with the receiving chamber to return fluid from the receiving to the first chamber, and means to control the size of the opening.

8. Separating and collecting mechanism comprising a chamber through which a stream of particle laden fluid is adapted to flow, means to impart a whirl to the fluid and particles, means to separate from said stream a portion of said fluid and particles entrained therein, a receiving chamber to receive the said separated fluid and particles, means beyond the separating means in the direction of flow to remove the whirl from the fluid, an opening in the first chamber beyond the whirl removing means in the direction of flow and communicating with the receiving chamber to return fluid from the receiving to the first chamber, means to control the size of the opening, and baffle mechanism in the receiving chamber to separate particles from the fluid returning to the first chamber.

9. Separating and collecting mechanism comprising a Venturi device having an inlet cone, a throat, and an outlet cone, means to direct a fluid having particles entrained therein into the inlet cone with a whirling motion, means to skim off particles and fluid adjacent the wall of the inlet portion, means to remove the whirling motion from the fluid entering the venturi throat, a chamber to receive the skimmed particles and fluid, and means to return fluid from

the chamber to the venturi throat at a point beyond the whirl removing means in the direction of flow.

5 10. Separating and collecting mechanism comprising a Venturi device having an inlet cone, a throat, and an outlet cone, means to direct a fluid having particles entrained therein into the inlet cone with a whirling motion, a secondary inlet cone spaced from the first inlet cone to form an annular skimming slot, a chamber to receive the skimmed particles and fluid, vanes in the secondary cone to remove the whirl from the fluid, and means to return the fluid from the chamber to the Venturi throat.

15 20 25 11. Separating and collecting mechanism comprising a Venturi device having an inlet cone, a throat, and an outlet cone, means to direct a fluid having particles entrained therein into the inlet cone with a whirling motion, a secondary inlet cone spaced from the first inlet cone to form an annular skimming slot, a chamber to receive the skimmed particles and fluid, vanes in the secondary cone to remove the whirl from the fluid and an aperture in the Venturi throat communicating with the chamber to return fluid from the chamber to the throat.

WILLIAM SPENCER BOWEN.
